United States Patent Office

Des. 211,602
Patented July 2, 1968

211,602

LAUNDRY MACHINE

Thomas R. Smith, Newton, Iowa, assignor to The Maytag
Company, Newton, Iowa, a corporation of Delaware

Filed Aug. 15, 1967, Ser. No. 8,267

Term of patent 14 years

(Cl. D49—1)

Fig. 1

Fig. 2

Fig. 3

FIGURE 1 is a perspective view showing the front and side of a laundry machine, showing my new design;

FIGURE 2 is a front elevation view of the laundry machine shown in FIGURE 1; and

FIGURE 3 is a perspective view showing the top, rear, and side of the laundry machine of FIGURE 1.

The side not shown has substantially the same appearance as the side shown.

I claim:

The ornamental design for a laundry machine, as shown and described.
